BLOWER FOR FIREPLACE FIRE

William V. Dennis, Jr., Atherton, Calif., assignor
to Van Art, Inc., San Francisco, Calif., a cor-
poration of California

Application January 29, 1952, Serial No. 18,289

Term of patent 14 years

(Cl. D62—2)

To all whom it may concern:

Be it known that I, William V. Dennis, Jr., a citizen of the United States, residing at 164 Selby Lane, Atherton, California, in the county of San Mateo and State of California, have invented a new, original and ornamental Design for a Blower for Fireplace Fire, of which the following is a specification, reference being had to the accompanying drawing, forming part thereof.

Fig. 1 is a side elevational view showing my new design for a blower for fireplace fire.

Fig. 2 is a rear elevational view of the design of Fig. 1.

Fig. 3 is a front elevational view of the design of Fig. 1.

Fig. 4 is a top plan view of the design of Fig. 1.

I claim:

The ornamental design for a blower for fireplace fire, as shown.
